UNITED STATES PATENT OFFICE.

CLARENCE E. LOMAX, OF CHICAGO, ILLINOIS, ASSIGNOR TO AUTOMATIC ELECTRIC COMPANY, OF CHICAGO, ILLINOIS, A CORPORATION OF ILLINOIS.

CALL-INDICATING SYSTEM.

Application filed April 19, 1920. Serial No. 374,887.

To all whom it may concern:

Be it known that I, CLARENCE E. LOMAX, a citizen of the United States of America, and a resident of Chicago, Cook County, and 5 State of Illinois, have invented certain new and useful Improvements in Call-Indicating Systems, of which the following is a specification.

My invention relates in general to a call 10 indicating system in which means is provided for indicating to a calling subscriber whether or not he is connected with the called subscriber with whom he desires connection and relates more specifically to a series of 15 lamp signals arranged before each calling subscriber in tens and units groups in such a manner as to set up before the calling subscriber an indication of the number of the called station with which he is actually 20 connected in order that he may check up and see that his call was properly completed to the subscriber desired.

It will be understood that my invention as explained above may be applied to any 25 desired type of automatic telephone system and is not confined to use with the system herein shown.

In the embodiment shown in the drawings I have illustrated my invention in connection 30 with a so called telautographic system, as the use of my invention in such a system would be of exceptional value due to the fact that no conversation is carried on between calling and called parties. The telautograph system as now used is a device 35 for communicating from one station to the other by writing and is used in banks and other large concerns to transmit inquires or orders from one department to another. 40 I believe that this is the first time an automatic connector switch and calling device have been used to complete connections between telautograph lines.

In the drawings I have shown in Fig. 1 45 a telautograph station A only diagrammatically as having a receiving device REC. and a transmitting device TR. The device REC. consists of a roll or tape with means for reproducing thereon the message sent in. 50 The device TR. consists of an electromechanical pencil and a pad for writing out the message to be forwarded to the receiving or called station. The telautograph device is not a part of my invention. At H (Fig. 1) 55 is shown an automatic connector switch of

the type, mechanically, such as is shown in the patent to Keith Erickson and Erickson #815176 granted April 21, 1905. Associated with the station A is a calling device CD and a key K, the calling device being included 60 in a call line to the switch H for operating the same and the Key K also included in said call line for opening and closing said line before and after a call.

In Fig. 2 I have shown at B, one of the 65 called stations, similar in all respects to station A, which is accessible to the connector switches H of all other lines or stations.

In Fig. 3 I have shown a diagrammatic layout of the connections from 2 levels of 70 a switch H with the connections to the lamp signals.

Also in Fig. 1 I have shown two series of lamps arranged in horizontal strips and 75 one set of which would be preferably mounted above the receiving device of each station. These lamps are connected to certain contacts accessible to the wipers of the switch H and one lamp in each set is lighted whenever the switch stands in connection 80 with a called station.

I will now explain in detail the method of operation of the system when a station such as A desires to communicate with a station such as B (Fig. 2). When the party 85 at substation A desires to call he first throws the call key K to close the line 3 from the calling device CD to the line relay 4 of the individual connector switch H. Relay 4 energizes over this circuit and closes a circuit for slow relay 5 to energize the same, relay 5 connects ground through spring 6 and front contact to the private normal conductor 7 to prevent any other station from connecting with the calling line, opens the 90 circuit of relay 8, opens a point in the circuit of release magnet 9 at springs 10 and 11, and prepares a circuit for vertical magnet 13 and slow relay 14 at springs 10 and 12.

Now the calling subscriber will operate 100 the calling device CD in accordance with the two digits of the called number which in this case is assumed to be #11. When the impulse or impulses for the first digit operate relay 4, said relay in turn transmits a corresponding number of impulses through relay 14 and magnet 13 to step the wipers to that level in which the terminals of the desired line are located. Relay 14 remains 105 energized during the impulses of this digit 110

2 to open the springs 15 and hold a new circuit closed for itself and magnet 13 through springs 16 and 17 after the off normal springs 18 have opened and springs 19 have 5 closed on the first vertical step.

After the wipers reach the first level and the wiper 20 is therefore in engagement with the first vertical contact 21 then relay 14 will fall back to close springs 15 and to close 10 springs 16 and 22 to prepare a new circuit to the rotary magnet 23 and relay 24. The closure of springs 15 connects ground to wiper 20 and thence through contact 21 to the tens lamp #1 to light the same and a 15 branch of this circuit passes through relay 25 to battery. Relay 25 energizes, closes a locking circuit for itself at springs 26 and also connects the ground from springs 39 and 6 of relay 5 through said springs 26 to 20 the lighted lamp, thereby holding said lamp lighted independent of wiper 20 and contact 21. It will be understood that this wiper 20 passes over contacts 21, etc., as the switch is moved vertically and then moves away from 25 these contacts as the switch is moved in a rotary direction.

Now as the calling device is operated for the next series of impulses relay 4 again vibrates in response thereto to, in this case, repeat 30 a like number of impulses to the rotary magnet 23 and slow relay 24 in multiple. The rotary magnet therefore operates to step the wipers of the switch onto the first set of contacts in the first level, to which contacts 35 the station B is connected. Should the called line be busy in another call then a ground would be present on the private conductor thereof either from the switch of this line or from the wiper of some other switch 40 resting on the multiple contacts in said other switch.

Before relay 24 has time to fall back therefore a circuit would be completed from ground on conductor 27, through wiper 28, 45 springs 29 and 30, springs 31, and relay 32 to battery.

Relay 32 energizes to open the circuit of the rotary magnet at springs 33, and prepares a locking circuit through springs 34 50 and 35 for itself after relay 24 falls back. In this case therefore the calling party will be unable to communicate with the called man and will operate key K to open the call circuit 3, thus allowing the relay 4 to fall back and in turn relay 5 falls back to release the switch and restore all relays of the switch H to normal, thereby extinguishing the ten's lamp.

If however, the called station is idle then 55 relay 32 will not energize and when relay 24 falls back after the second digit a circuit will be completed for the switching relay 38 as follows: From ground through spring 6 of relay 5, spring 39, springs 34 and 40, lower winding of relay 38, springs 41 and

29, wiper 28, conductor 27, through the springs of the called party's connector switch corresponding to springs 6 and 42 of the switch H, and through the relay of 60 said switch corresponding to relay 8 of switch H. This relay 8 opens the calling circuit of the called line to prevent the called man's switch from being operated, and relay 38 energizes to open the springs 43 and 31 and closes a locking circuit through its own upper winding from ground through springs 6 and 39, springs 44 and 45 and upper winding of relay 38 to battery. The closure of springs 44 and 45 also closes a circuit for the relay 46 to switch the telautograph lines 47-50 inclusive through to the conductors of the called station, and removes a short circuit from the resistance 51 at springs 52 to cut down the current flowing in relay 4. A branch of this latter circuit may also be traced from ground through springs 6 and 39, and springs 44 and 45, through wiper 36 and its engaged contact 37 to lamp #1 of the row of units lamps. The closure of springs 44 and 53 also places ground direct on the wiper 28 to make the called line busy to other calls.

The calling party will now see the lamps 95 #1 of the units and tens rows lighted and will know that his connection has been completed to the #11 station and he will proceed to write his message on the telautograph sender in the usual manner and receive a written answer on his receiving device "Rec."

When the call is finished the party at station A will operate the key K to open the call circuit 3, thus allowing relay 4 to fall back and in turn relay 5 falls back to release the switch and restore all relays of the 105 switch H to normal thereby extinguishing the lamps of the tens and units.

It will be understood that this switch H may be used to extend any number of conductors such as 47-50 inclusive and that the four wires shown are only alternative as the telautograph may be in some cases operated over only 2 conductors and in other cases may require more than 4.

It will be understood that I have shown 115 only a portion of the banks of the connector H in Fig. 1. These contacts being preferably arranged in double banks of 200 contacts each, that is the wipers have ten steps up and ten rotary. The wipers 28 and 36 being in one pair and operating over one set of banks having double contacts, of which 37 and 54 being the first set. Also each pair of line wipers terminating conductors 47 and 48 and 47 and 50 have access to a separate 120 double bank of 200 contacts.

In Fig. 3 I have shown a diagrammatic representation of the wiring of the vertical contacts and also the multiplying of the special private contacts accessible to wiper 36. It will 125

be understood that the line banks of the 100 connectors in the system will all be multiplied so that each has access to all the lines of the system. The contacts of each bank 5 are arranged as usual in ten horizontal rows of two each, there being one vertical contact for each row. In Fig. 3 I have shown 2 rows or levels of the special bank contacts and have shown how they are multiplied 10 vertically that is all the first contacts in each row such as 54 and 54' are multiplied together and are connected to the #1 units lamp while all the second contacts have a similar multiple and connect with the second units 15 amp, etc.

From the above description it will be understood that I have devised a very efficient method of extending a telautographic line to any one of a plurality of other stations by 20 means of an automatic switch and have also provided a very efficient call indicating or registering system whereby a call initiating party may be sure that he is in connection with the desired called station independent 25 of any listening device.

Having fully described and ascertained the features and aspects of my invention what I consider to be new and desire to have protected by Letters Patent will be pointed out 30 in the appended claims.

What I claim is:

1. In a telatograph system, a plurality of stations each having means for sending and receiving written messages, a calling device 35 for each station, an automatic switch controlled by the calling device of a calling station to extend a connection to a called station and indicating means controlled by the operation of said switch for indicating 40 to the calling station to what station he is in connection with.

2. In a telatograph system an automatic switch, lines accessible to said switch divided into decimal groups, means controllable from 45 one of said lines for operating said switch to connect with any other of said lines, and a series of tens and units lamps, one tens lamp for each decimal group and one units lamp for each line in a group, one lamp in each 50 series being lighted when connection is made with any line to indicate to the calling line the number of the called line.

3. In a telatograph system, stations, an automatic switch for connecting one station 55 to another, said switch having a step by step vertical and rotary movement over terminals of lines, a series of lamps one for each vertical step and another series one for each rotary step, and means for lighting one lamp 60 in each series when the switch is connected to any called line.

4. In a telatograph system, stations, an automatic switch for connecting one station to another, said switch having a step by step 65 vertical and rotary movement over terminals

of lines, a series of lamps one for each vertical step and another series one for each rotary step, means for lighting one lamp in each series when the switch is connected to any called line, and means for maintaining 70 both lamps lighted until the connection is released.

5. A system for extending one telautograph line into connection with another comprising a plurality of automatic progressive- 75 movable switches, a calling device at each station for controlling one of said switches, and means controlled by the operation of said switch for setting up before the calling subscriber the number of the line with which 80 he is connected after the switch is operated by the calling device to extend such connection.

6. In a telautograph system, an automatic switch for extending connections from one line to another, wipers for said switch for extending connections, a vertical wiper for said switch having contacts accessible thereto, one for each level, a rotary wiper having contacts accessible to it, one for each rotary 85 step of the switch, means for operating said switch vertically in response to one digit, and rotary in response to another, a series of lamps one for each vertical and one for each rotary contact, one lamp in each series 90 lighted by means of said wipers and maintained lighted until the switch is released.

7. In a telautograph system, a station, a telautographic receiver and transmitter therefor, an automatic switch accessible to 100 the line of said station and a calling device at the station for controlling said switch, a set of signals at said station arranged in series, one series for each digit and means controlled through the medium of said 105 switch for operating one signal in each series to indicate to the calling station the number of the line to which connection has been extended.

8. In a telautograph system, an automatic 110 switch for extending connections from one station to another, a bank of contacts accessible to said switch and a plurality of wipers cooperating therewith, the contacts being arranged in rows or levels, the contacts in 115 all levels of one set being multiplied vertically and connected to a series of lamps, one for each rotary step of the wipers, and another set of contacts one for each row of contacts connected to another series of lamps, whereby when a switch is operated the lamps lighted indicate the position of the wipers.

9. In a switching system for telautograph lines, an automatic step by step switch individual to a calling station and operable for connecting said station with any one of a plurality of other stations, a manually operable calling mechanism for transmitting impulses to said switch in accordance with the number of a desired called station, and 125 130

separate indicating means for enabling the calling party to check the operation of said switch to ascertain whether or not connection has been extended to the right 5 station.

10. In a switching system for telautograph lines, an automatic step by step switch individual to a calling station and operable for connecting said station with any one of 10 a plurality of other stations, a manually operable calling mechanism for transmitting impulses to said switch in accordance with the number of a desired called station, and a visual indicator associated with said switch 15 for indicating the number of the station to which the connection is extended in order to enable the calling party to check the number connected with against the number called.
20. In a switching system for telautograph lines, an automatic switch individual to a calling station, wipers for said switch operable to extend a connection to any one of a plurality of other stations, a manually 25 operable calling device for transmitting impulses to said switch in accordance with the number of a desired called station, said switch being responsive thereto to advance

its wipers into connection with the desired station, and a visual indicator controlled by the switch for indicating to the calling party the exact position of the switch wipers, to enable such calling party to check the number of the station connected with against the 30 number of the station called.

35. 12. In a switching system for telautograph lines, an automatic switch individual to a calling station, wipers for said switch operable to extend a connection to any one of a plurality of other stations, a manually 40 operable calling device for transmitting impulses to said switch in accordance with the number of a desired called station, said switch being responsive thereto to advance its wipers into connection with the desired 45 station, and a series of indicating lamps selectively controlled by the switch for indicating to the calling party the exact position of the switch wipers, to enable such calling party to check the number of the station 50 connected with against the number of the station called.

Signed by me at Chicago, Cook County, Illinois, this 15th day of April, 1920.

CLARENCE E. LOMAX.
